THEFT PROOF FILL PIPE CLOSURE

Filed Jan. 11, 1945

UNITED STATES PATENT OFFICE

2,411,505

THEFTPROOF FILL PIPE CLOSURE

Earl B. Chamberlain, Fort Wayne, and Robert M. Kolter, Decatur, Ind.

Application January 11, 1945, Serial No. 572,330

5 Claims. (Cl. 220—86)

1

This invention relates to a theft proof fill pipe closure for automobiles. More especially, it relates to a fill pipe closure which does not utilize a lock of any of the usual types.

Numerous attempts have been heretofore made to prevent the removal of gasoline from automobile tanks through the fill pipe of such tanks, either by siphoning, pumping, or other methods. Usually these devices take the form of a fill cap which is removable from the fill pipe, but is locked in position by a key-operated lock.

These devices are often inconvenient in that the keys thereto are not available when required. Sometimes water accumulates in the locks and freezes. Frequently, the caps are not replaced on the fill pipe after filling and become lost.

An object of the invention is to provide a closure which, once it is installed, will never be removed.

Another object of the invention is to provide a closure which is easily installed.

Yet another object of the invention is to provide a closure which opens inwardly in response to the insertion of a dispensing nozzle.

It is another object of the invention to provide a closure which returns automatically to the closed position as soon as the dispensing nozzle is withdrawn.

Another object of the invention is to provide a fill pipe closure which will accept liquid at substantially the normal rate of from 12 to 15 gallons per minute and yet will prevent the insertion of a tube or pipe of any substantial size.

Still another object of the invention is to provide a closure which is not removable after installation.

A further object of the invention is to provide a fill pipe closure which prevents the insertion of means for removing liquid from the associated tank.

These and other objects will become apparent from a study of this specification and the drawing which is attached hereto and forms a part hereof in which:

Figure 1 is a vertical sectional view of the fill pipe and the fill pipe closure taken substantially on the line 1—1 of Figure 2.

Figure 2 is a view taken from the bottom of Figure 1 showing the perforated portion of the stirrup.

Figure 3 is a horizontal view, partly in section and partly in plan, taken on the line 3—3 of Figure 1.

Referring now to Figure 1, the numeral 1 represents the fill pipe of the usual automobile,

2

which is usually a straight-sided or cylindrical tube. The tube is usually flanged at 3 and turned inwardly as at 4 to form a sealing surface 5. The flange is usually notched in two diametrically opposed places 7 to receive locking projections on the usual fill pipe cap (not shown).

The fill pipe closure comprises an annular ring 9 to which is fixed an annular gasket 11 which is adapted to engage the fill pipe surface 5. 10 To the inner periphery of the ring 9 is fixed, as by welding or in any other suitable manner, a stirrup 13, which has a circular central plate or baffle 15, provided with a plurality of perforations 16, and two upwardly extending arms 17 which are fixed at their free ends to the ring. The arms extend substantially at right angles to the baffle. The arms 17 are slightly less in width than the notches 7 and are spaced from each other so that the distance from the exterior surface of one arm to that of the other is slightly less than the distance from the inner edge of one notch to that of the other. Thus the notches will readily receive the arms and yet will hold the arms and the closure assembly as a whole against rotation in the fill pipe.

A projection 19 is punched from each of the arms 17 and projects upwardly and outwardly. The distance across the outer ends of the projections is greater than the distance between the edges of the notches 7, so that when the device is in position in the fill pipe, the ends of the projections will engage the flanges 5 and prevent withdrawal of the assembly. The projections are sprung inwardly by the edges of the notches during insertion.

A cylindrical guide 21 is staked or otherwise fixed in a central opening 23 of the baffle 15. A stem 25 is slidably mounted in the opening 27 of the guide and screwed or otherwise fixed to the upper end of the stem is the closure member 29. 40 A coiled compression spring 31 surrounds the guide and stem and bears at one end on the baffle 15 and at the other on the underside of the closure member 29.

The distance between the inner surfaces of the arms is greater than the maximum diameter of member 29 so that the latter may be forced downwardly between the arms.

A cover 33 is provided with an opening 35 which is smaller in diameter than the closure member 29. The cover is bowed outwardly at 37 to provide a slanting, curved surface which will assist in shedding water and which will present a pleasing appearance.

50 The outer periphery of the cover is crimped

about the periphery of the ring 9 and gasket 11 at 39 to hold them securely in place. The cover is then flanged inwardly and downwardly at 41 and extends below the upper end of the fill pipe to prevent water from running from the cap onto the surface 5.

The gasket 11 is preferably made of relatively thick and resilient material such as cork or synthetic rubber so that the gasket will be compressed and held compressed by the engagement 10 of the projections 19 and the flange 3 of the fill pipe.

Operation

To install the closure, the usual fill pipe cap is removed and the assembly described above is entered in the fill pipe with the arms 17 riding in the notches 7 of the fill pipe flange 3. The assembly is then forced downwardly so that the projections 19 are forced inwardly. The gasket is compressed until the projections clear the flange, whereupon they spring radially outwardly again under the flange 3 to hold the gasket compressed and to hold the assembly in the fill pipe.

When the tank is to be filled, the dispensing nozzle is placed on the closure member 29 and force is applied thereto to depress it against the force of the spring 31. Preferably the closure member should be depressed all the way. When the usual nozzle valve is opened, the gasoline flows outwardly and downwardly around the baffle 15 into the tank. Some of the liquid also flows through the holes 16.

When the nozzle is withdrawn, the spring 31, acting on the closure member, forces it upward until it contacts the cap 33 and closes the pipe. The closure member thus prevents the entry of dirt, water or other foreign matter.

It is obvious that various changes may be made in the form, structure and arrangement of parts without departing from the spirit of the invention. Accordingly, applicants do not desire to be limited to the specific embodiment disclosed herein primarily for purposes of illustration; but instead, they desire protection falling fairly within the scope of the appended claims.

What we claim to be new and desire to protect by Letters Patent of the United States is:

1. The combination with a fill pipe having an end flange provided with opposed notches, a support comprising an element adapted to rest upon the outer side of the flange, arms fixed to and depending from said element and passing through said notches, yieldable means projecting outwardly and upwardly from the outer sides of said arms for engaging the inner side of said flange to prevent withdrawal of the support, and a baffle supported by said arms transversely of said pipe to prevent the insertion of liquid removing means.

2. The combination with a fill pipe having an end flange provided with opposed notches, a support comprising an element adapted to rest upon the outer side of the flange, arms fixed to and depending from said element and passing through

said notches, a baffle supported by said arms transversely of said pipe to prevent the insertion of liquid removing means, a cap fixed to said support and having a fill opening, a closure, said arms being disposed to guide said closure, guide means in said baffle for said closure, and yieldable means for urging said closure into closing position with respect to said fill opening.

3. The combination with a fill pipe having an end flange provided with opposed notches, a support comprising an element adapted to rest upon the outer side of the flange, arms fixed to and depending from said element and passing through said notches, yieldable means projecting outwardly and upwardly from the outer sides of said arms for engaging the inner side of said flange to centralize the support in the pipe and to prevent withdrawal of the support, a baffle supported by said arms transversely of said pipe to prevent the insertion of liquid removing means, a cap fixed to said support and having a fill opening, a closure, guide means in said baffle for said closure, and yieldable means for urging said closure into closing position with respect to said fill opening.

4. The combination with a fill pipe having an end flange provided with opposed notches, a support comprising an element adapted to rest upon the outer side of the flange, arms fixed to and depending from said element and passing through said notches, outwardly directed spring fingers on said arms, adapted to engage said end flange and side walls to prevent withdrawal of the support from and to centralize said support in said pipe, a baffle supported by said arms transversely of said pipe to prevent the insertion of liquid removing means, a cap fixed to said support and having a fill opening, a closure, guide means in said baffle for said closure, yieldable means for urging said closure into closing position with respect to said fill opening, said arms being constructed and arranged to serve as additional guide means for said closure.

5. The combination with a fill pipe having an end flange provided with opposed notches, a support comprising an annular element and a gasket adapted to rest upon the outer side of the flange, arms fixed to and depending from said element and passing through said notches, outwardly directed spring fingers on said arms constructed and arranged to engage said flange to hold said support against withdrawal from the pipe, to hold said gasket compressed and to centralize said support, a baffle supported by said arms transversely of said pipe to prevent the insertion of liquid removing means, a cap crimped about and supported on said element, said cap having a fill opening, closure means, guide means in said baffle for said closure and yieldable means for urging said closure into closing position with respect to said opening.
